UNITED STATES PATENT OFFICE

EARL HOSKINS, OF PHOENIX, ARIZONA, ASSIGNOR OF ONE-THIRD TO J. D. FITZPATRICK,
OF PHOENIX, ARIZONA

AIR COOLING SYSTEM

Application filed September 13, 1930. Serial No. 481,783.

This invention appertains to new and useful improvements in air cooling systems and more particularly to a system whereby the air is cooled by passing between two tanks containing a cooling agent.

The principal object of this invention is to provide a cooling system wherein the air does not contact with any liquid medium.

Other important objects and advantages of the invention will readily become apparent to the reader of the following specification.

In the drawings:

Figure 1 represents the vertical fragmentary sectional view through a building equipped with the improved system,

Figure 2 represents a vertical sectional view through one of the cooling units,

Figure 3 represents a horizontal sectional view through the cooling unit taken substantially on line 3—3 of Figure 2 looking downwardly.

Figure 4 represents a vertical sectional view through a slightly modified form of the invention,

Figure 5 represents a vertical sectional view taken substantially on line 5—5 of Figure 4.

Referring to the drawings wherein like numerals designate like parts, the numeral 5 represents the room of a building, with numeral 6 designating the floor and numeral 7 the ceiling. Numeral 8 represents one side wall of the building.

Numeral 9 generally refers to one of the cooling units which includes a container 10 of cylindrical shape. This container 10 has a tank 11 mounted therein and surrounding the tank 11 is a jacket 12, said jacket being in spaced relation from both the tank 11 and the container 10. The upper ends of both the tank 11 and jacket 12 are constricted while the interior of the tank 11 and the interior of the container 10 are communicated by by-passes 13 extending through the tank

and jacket at their upper constricted ends. The jacket 12 is supported upon the inlet pipe 14 and as is clearly shown in Figure 2, the lower ends of the tanks 11 and container 10 are communicated by by-passes 15. A 50 funnel 12a is mounted in the container 10 and has notches 12b in the lower end thereof so that water caught by the funnel will be directed onto the upper reduced end of the jacket 12. 53

The upper end of the jacket 12 merges into a cold air outlet or pipe 16 in which the pump 17 is located. This pipe 16 extends to an outlet head 18 preferably located adjacent the ceiling 7 of the room, while the head 18' on the inlet pipe 14 is located in the floor 6 of the room and may be in the form of a register.

A conventional cooling tower consists of 65 vertically disposed bars 19 supporting the annular fins 20 in vertically spaced arrangement, the lower fin 20 resting upon the upper end of the container 10 so that water discharged from the nozzle 21 of the inlet water pipe 22 will fall both into the flared end 23 70 of the pipe 24 which projects upwardly from the constricted end of the tank 11 and into the space between the container 10 and the jacket 12, a deflector 25 being located within the tank 11 at its apex point so as to deflect water to permit it to run down the inner side of the tank in a film. 75

The upper end of the jacket 12 is constructed so that the water from the nozzle 21 will also run down the outer side of the jacket in a sheet or film. 80

It can now be seen that air will enter through the pipe 16 from the pump 17 and pass through the space 26 between the tank 11 and the jacket 12 to escape through the outlet pipe 14. Obviously the air in passing through this space will be cooled by both the wall of the tank 11 and the jacket 12. This cooling action takes place without any actual contact of the air with the water which 90

is highly desirable to maintain the low water content in the air.

Figures 4 and 5 disclose a somewhat modified form of the invention, the same disclosing a substantially rectangular shaped housing 27 provided with the end wall 28. The lower ends of the wall 28-28 are provided with openings within which the ends of the air pipes 29 are secured.

Numeral 30 represents a box structure enclosing the ends of the pipe 29 at the lower end of one of the end walls 28 and this forms the intake for the air. An adjustable closure 31 permits regulation of the air intake. It can be seen that a funnel 32 encloses the ends of the air tube 29 at the opposite end wall 28 and merges with a lead off pipe 33 to the point where the cool air is to be discharged.

Numeral 34 represents a platform supporting an electric motor 35 and a pump 36 driven thereby. Numerals 37 represent drain pipes on the bottom of the housing 27, while numeral 38 represents an outlet pipe leading to the spray line 39 located in the top of the housing 27. Angle irons 40 are arranged longitudinally within the housing 27, each disposed, directly between uppermost air tubes 29 with its channel head side downward. Discharging from the spray line 39 will be deflected by the angle iron 40 so as to pass downwardly over the air tubes 29.

As the water descends over the tubes 29 the air passing through the tubes will be efficiently cooled.

While the foregoing specification sets forth the invention in specific terms, it is to be understood numerous changes in the shape, size, materials may be resorted to without departing from the spirit or scope of the invention as claimed hereinafter.

Having thus described my invention, what I claim as new is:

1. An air cooling apparatus comprising a container, a double wall structure arranged within the container and in spaced relation thereto, a by-pass communicating the interior of the container with the interior of the double wall construction, a feed line for discharging a cooling medium on to the double wall construction, an air inlet for the double wall construction and an outlet for the double wall construction.

2. A cooling apparatus comprising a container, a tank mounted within the container, a spaced bracket surrounding the container being disposed in spaced relation to the container, a by-pass communicating the interior of the container with the interior of the tank, an air inlet to be spaced between the tank and the jacket, and an air outlet communicating with the space between the tank and the jacket.

3. A cooling apparatus comprising a container, a tank mounted within the container, a spaced bracket surrounding the container

being disposed in spaced relation to the container, a by-pass communicating the interior of the container, with the interior of the tank, an air inlet to be spaced between the tank and the jacket, and an air outlet communicating with the space between the tank and the jacket, and means for directing the cooling medium to the inside of the tank and to the outside of the jacket.

In testimony whereof I affix my signature.

EARL HOSKINS.
